UNITED STATES PATENT OFFICE.

WILHELM FRANS RIEMVIS, OF WELTEVREDEN, JAVA, DUTCH EAST INDIA.

MOTOR-CAR AMBULANCE BARROW.

Application filed October 14, 1922. Serial No. 594,586.

To all whom it may concern:

Be it known that I, WILHELM FRANS RIEMVIS, a subject of the Queen of the Netherlands, and residing at 62 Kramat, Weltevreden, Java, Netherland East India, have invented certain new and useful Improvements in Motor-Car Ambulance Barrows, of which the following is a specification.

This invention relates to an adjustable ambulance-barrow designed to be placed in motor-cars and composed of a number of pieces arranged for the purpose of being quickly mounted and dismounted, and which barrow can be easily carried along in a dismantled state in every motor-car without absorbing considerable place, while it is erected in case of need upon iron feet over the seats in the carriage. Most motor-cars, except however two-seaters, are suitable for providing such ambulance barrows.

The ambulance-barrow according to the invention consists substantially in a chain frame of rectangular shape, of which the space enclosed by the chain can be covered by a foldable or rollable cloth secured to the chain and serving as the litter for transport of a sick person and the said frame being suspended by means of springs or other kind of elastic suspension at its four corners to the iron feet, which are adjustable and composed of several pieces, adapted to be quickly fixed and erected between the seats of the carriage.

In order that the invention may be clearly understood an embodiment of it is shown by way of example in the accompanying drawing, in which:

Fig. 1 is a top plan,

Fig. 2 is a side elevation, and

Fig. 3 a front elevation of an adjustable motor-car ambulance-barrow according to the invention.

Referring to the drawing the ambulance-barrow is composed of a chain 1, stretched rectangularly by means of four rings 2, disposed at the corners of the frame, while from distance to distance in cross direction bows 3 curved a little bit downward may be hooked into eyes 4 of the chain. The rectangle formed by the chain is covered by a cloth which constitutes the litter for the sick person to be laid upon. The rings 2 at the four corners of the chain are suspended between the four feet by means of springs 5 hooked in rings provided at the upper ends of the four feet.

The said four feet, which can be fixed upon the floor of the carriage, are composed of a number of separate parts adapted to be readily erected or taken to pieces. In the represented embodiment each foot is composed of five parts.

The first part consists in a piece of iron bowed at right angle. The horizontal portion 6 made of band iron is fixed upon the floor of the carriage at a short distance in front of the seats by means of screws or bolts, while the upright portion of circular section is fixed in any proper way to the lower part of the seat, e. g. by means of a bow 7 secured by clamping bolts. The said upright portion is preferably provided with a projecting rim or flange 8 for supporting the second part of the foot.

This second part consists in a steel pipe 9, adapted to be sleeved over the upper end of the first part. The upper end of the said pipe is provided with holes in which a pin 10, suspended on the pipe by means of a small chain, can be put for the sake of adjusting the height of the third part of the foot.

The third part consists in an iron rod 11, which when erecting the barrow is put in the pipe 9 until it rests upon the pin 10 put into one of the holes. The upper end of the rod 11 is of a smaller section and provided with screw thread.

The fourth part is made of spring steel and consists in a strip 12 provided with an elongated slot extending in the longitudinal direction nearly from end to end of the strip. At one end the strip 12 has a threaded hole adapted to be screwed upon the threaded end of the rod 11, on which it can be secured by means of a nut 13.

The fifth part is also made of spring steel and rectangularly curved. The longest and horizontal strip 14 is provided with a hole having therein a clamping bolt 15, which passes also through the slot in the strip 12, so that the said two strips can be clamped to one another by screwing the nut, which is represented as a butterfly nut, on the bolt 15. By pushing the bolt 15 forward or backward in the slot of the strip 12, the litter can be disposed more at the front or at the rear of the carriage and can also be lengthened or shortened. On the vertical strip 16 is fixed a cross piece 17 provided with a series of rings 18, each of which can be used for suspending the springs 5, so that in this way

the litter can be positioned more to the left or to the right of the carriage or changed in width.

It appears from the above that the litter 5 is adjustable in length and in width and that its position towards the carriage and the seats can be changed in all directions to adapt the barrow to the shape and dimensions of the carriage.

10 It will be understood that these several parts when taken to pieces want but little place, so that they can easily and without trouble be carried along under the seats in the motor-car. In case of need after fixing 15 the first part of the feet upon the floor of the carriage, the ambulance-barrow can be made ready for use in a minimum of time by assembling the several parts of the feet and of the chain frame with cover.

20 The sinking through of the cloth is highly reduced in consequence of the strain of the feet and of the cross bows. A convenient spring action is obtained by the suspension springs and by the elasticity of the strips of 25 spring steel in the feet.

The above embodiment of the invention has only been described by way of example and it is evident that the ambulance-barrow can be varied within wide limits without departing from the spirit of the invention, as 30 the several parts of the adjustable barrow

and feet are susceptible of many modifications in their construction.

Having now particularly described and ascertained the nature of my said invention 35 and the manner in which it is to be performed, what I claim as new and wish to secure by Letters Patent is:

1. An ambulance-barrow support, comprising a plurality of collapsible members 40 for supporting a bed bottom, each member comprising in combination, a foot element, an extensible upright element, a horizontally adjustable head element, and a bed bottom attaching means carried by the head element. 45

2. An ambulance-barrow support, according to claim 1, the extensible upright element telescoping on the foot element and itself comprising telescoping members with means for holding the said members in adjusted 50 position.

3. An ambulance-barrow support, according to claim 1, the attaching means including a plurality of spaced attaching elements whereby to adjust the width of a bed bottom. 55

4. An ambulance-barrow support according to claim 2, the composite head element having a horizontally slid able bolt and slot connection.

In testimony whereof I affix my signature. 60

WILHELM FRANS RIEMVIS.
